US00D851511S

(12) **United States Design Patent** (10) **Patent No.:** **US D851,511 S**
(45) **Date of Patent:** **** Jun. 18, 2019**

(54) **LEVEL**

(71) Applicant: **Milwaukee Electric Tool Corporation**,
Brookfield, WI (US)

(72) Inventors: **Joseph Burge**, Milwaukee, WI (US);
Bryant Deakins, Kansasville, WI (US);
Michael Wyatt, Waukesha, WI (US)

(73) Assignee: **Milwaukee Electric Tool Corporation**,
Brookfield, WI (US)

(**) Term: **15 Years**

(21) Appl. No.: **29/633,853**

(22) Filed: **Jan. 16, 2018**

Related U.S. Application Data

(63) Continuation of application No. 29/564,229, filed on
May 11, 2016, now Pat. No. Des. 810,597.

(57) **CLAIM**

We claim the ornamental design for a level, as shown and described.

DESCRIPTION

FIG. 1 is a front perspective view from above of an embodiment of the claimed design;

FIG. 2 is a rear perspective view from above of the design of FIG. 1;

FIG. 3 is a rear perspective view from below of the design of FIG. 1;

FIG. 4 is a front view of the design of FIG. 1;

FIG. 5 is a rear view of the design of FIG. 1;

FIG. 6 is a right side view of the design of FIG. 1;

FIG. 7 is a left side view of the design of FIG. 1;

FIG. 8 is a top view of the design of FIG. 1; and,

FIG. 9 is a bottom view of the design of FIG. 1.

The ornamental design which is claimed is shown in solid lines in the drawings. The broken lines in the drawings are for illustrative purposes only and form no part of the claimed design.
